CLOSURE FOR RECEPTACLES

Percy M. Thorn, Reading, Conn.

Application July 21, 1932, Serial No. 623,757

14 Claims. (Cl. 221—60)

This invention relates to closures for receptacles.

It is an object of this invention to provide a new and improved closure of the type which may be easily opened without removing any separable parts, which when closed, will be substantially leak proof and which will remain leak proof substantially throughout the life of the device, and which may be used repeatedly without smearing the contents of the receptacle over the outside of the closure.

It is a further object to provide a new and improved closure which will be simple to manufacture and reliable and durable in its operation.

It is a further object to provide a new and improved device having a central opening provided with a closure which may be easily opened and closed by a simple manipulation of the head.

It is a further object to provide a new and improved closure which may be made in a form and of materials to resist a wide variety of liquids and fluids and which will be composed of few parts of a nature to be readily assembled for quantity production.

It is a further object to provide a new and improved closure which when used with a plastic mass such as tooth paste or ointment may be caused to cut off the extruded material from the container without the necessity of touching it with the fingers.

It is a further object to provide a new and improved closure which may be adapted to a wide variety of uses either with fluids such for example as toilet water, or glycerine, or with plastic substances such as salves or tooth paste and which may be applied to different types of containers whether bottles, cans or tubes, and which may be built into the container as a part thereof or which may be constructed as a separate element to be attached thereto.

It is a further object to provide a new and improved closure which will have a minimum of working parts and which may be assembled with a minimum of machine work upon the parts.

Other objects of the invention will in part be obvious and will in part appear hereinafter.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention, reference should be had to the following detailed description taken in

connection with the accompanying drawings, in which:

Figure 1 is a sectional view of the upper portion of a tube, adapted to be provided with a closure in accordance with this invention but having the upper portions removed to show the base construction.

Figure 2 is a sectional view similar to Figure 1 but with the upper portions of the closure in place.

Figure 3 is a modified construction adapted for use particularly where extreme tightness is desired.

Figure 4 is a plan view of the device of Figure 1 but with the shutter element added.

Figure 5 is a section of a further modification with the top portions of the closure removed. This modification is adapted to be used as a separate attachment to a container.

Figure 6 is a further modification adapted for use as a separate attachment for a container, but making provision for a particularly tight closure.

Figure 7 is a modification of the structure shown in Figure 3, showing a different method of effecting the tight closure.

Figure 8 is a modified form of the closure showing a different form of valve which is adapted for certain particular uses.

Figure 9 is a sectional view of a modification for clamping upon an ordinary bottle.

Figure 10 is a similar view of a further modification.

Figures 11 and 12 are plan and sectional views of a further modification adapted especially for pouring liquids.

Referring now more particularly to Figures 1 and 2, the numeral 10 designates a container which may be the ordinary type of soft metal tube employed for containing tooth paste or ointments or other similar products. At the upper portion the container is provided with a base member for the closure comprising a neck 11 having at its open end a substantially flat member 12 which closes the container save for a central opening 13. Immediately surrounding the opening 13 and concentric with it is an annular boss 14 adapted to serve as a shutter bearing surface.

On the outer periphery of the flat member 12 is an annular boss 15 which, in the form illustrated, extends above the boss 14 by an amount somewhat greater than the thickness of the shutter and hereafter to be described.

A form of the bosses 14 and 15 leaves an annular recess 16 between them and within this

recess there is provided at one point a radial slot 17. The outer surface of the neck 11 has an annular groove 18, defining an annular bead or rib 18a. Mounted upon the base of the closure is a cup shaped cap member 19 having a generally flat portion 20 generally parallel to the flat member 12 and provided with a central opening 21 in registry with the opening 13 in the flat member 12.

10 The cap member has a bearing surface 18a adapted to rest upon and mate with the surface 18 to maintain the cap member in position upon the base member, to insure the proper uniform contact between the shutter and the 15 shutter bearing surface and to permit free rotation of the cap.

20 The cup shaped member 19 also has a cylindrical wall 22 extending over the bead or rib 18a, the lower edges of this wall being spun over as shown at 23 into the groove 18 whereby the cup shaped member is held firmly and tightly but rotatably in place and may be rotated upon the base.

25 The flat portion 20 of the cup shaped member is preferably dished inwardly toward the opening as shown at 24 and upon the underside of this flat portion there is provided a boss 25 extending downwardly toward the bosses 14 of the flat member 12 to provide between the bosses a channel 30 for the movement of a shutter member. The flat portion 20 of the cup shaped member 19 is provided with a small hole 26 upon its undersurface.

35 The shutter member comprises in general a somewhat arcuate shaped flat plate 27 having near one end an upwardly projecting pin 28 adapted to fit into the hole 26 and having upon the other end a downwardly projecting pin 29 fitting into the slot 17. The proportions of these 40 parts are such that when the head is rotated, the pin 28 is carried from the position shown in full lines in Figure 4 to the position shown in dotted lines in the same figure, carrying the shutter with it from the full line to the dotted 45 position, causing the shutter to form a complete closure between the shutter bearing surfaces 14 and 25.

50 The height of the bosses 14, 15 and 25 is such that the bosses 14, and 25 bear upon both faces of the shutter with sufficient force to maintain a tight closure while the boss 15 fits snugly against the underside of the cap to prevent rocking of the cap in place, but without binding to prevent rotation.

55 The form of the invention illustrated in Figure 3 is similar to the foregoing except that in place of providing the upstanding rigid boss 14 to bear against the underside of the shutter, a washer of cork or other suitable material 31 in the form of a flat annular ring is inserted into an annular recess 32 in the flat member 12a, immediately surrounding the opening, the washer being of such size that it extends slightly above the lower surface 33 of the recess 16 and bears resiliently against the underside of the shutter and the neck of the container completely around the opening. This form of the invention makes it possible to apply the invention directly to containers of 60 glass or other similar substances which are difficult to machine to accurate size, and the resiliency of the cork assists in maintaining a closure which may be kept liquid tight.

65 In the form of the invention illustrated in Figure 5 the invention is applied to a separate

cap 35 which is shaped to receive the shutter and cap member 19 as previously described, but this separate cap is itself provided with some means of attaching it direct to the bottle. To this end it may be cemented on or, as illustrated, 5 it may be provided with female threads 36 adapted to mate with male threads upon the neck of the bottle. Even where these threads are provided, however, it may be desirable to cement the cap in place. In the illustration of 10 this modification the head and shutter are not shown in place because the assembly is similar to that shown in Figure 2.

15 The modification shown in Figure 6 is similar to that shown in Figure 5; that is, in this modification there is also provided a separate cap which may be attached to the top of a container or bottle. In this modification, however, the flat portion 12 has an opening 40 cut much larger than the opening 13 in the bottle or in the head 19, and within this opening 40 there is provided a suitable washer 41 in the form of a flat annular ring, having a central opening 13a substantially equal in diameter to the opening 13 in the bottle neck and in the head and its outer diameter such 20 as to cause it to fit snugly within the opening 40.

25 This form of the invention is adapted particularly for use where the container is of glass or other material difficult accurately to shape, since 30 with this form we need only see that the top face of the neck of the bottle is substantially flat and that the washer 41 is of the right length along its axis properly to bear up on the bottle and the shutter, as under such conditions when 35 the cap is screwed firmly in place upon the top of the bottle with the flat member 12 bearing upon the top of the bottle, the washer 41 will exert just the predetermined pressure upon the 40 underside of the shutter to effect a tight joint.

45 In the form of the invention illustrated in Figure 7 there is provided a resilient washer 44 resting upon the end of the neck of the container and the shutter 27 moves upon this washer, being held in place and moved by the cap member 45 as in the previous forms. A suitable slot 17a is cut through the washer to accommodate the pin 29. The container itself may be provided with an annular boss 45 surrounding the central 50 opening to cause the washer to bear firmly 55 against the shutter clear around the opening.

60 In this figure there is also illustrated a slightly different construction in that the upstanding boss 15 of the former constructions is replaced by a shoulder 43 within the cap member which bears 65 upon the flat surface of the top of the container and provides the necessary rigidity and spacing of the parts which is achieved in the former modifications by the boss 15. This still further reduces the labor of fabrication of the container which is of importance particularly when the container is made of some brittle substance such as glass. This feature can of course be used with any of the embodiments of the invention when desired.

65 The shutter illustrated in Figure 8 is similar to the shutter 27 in all respects except that it is arranged with an opening 21a which in one extreme position is adapted to be in complete registry with the opening 21, but which when rotated to the dotted line position, clearly closes the opening. This form of shutter may be utilized when desirable.

70 For many purposes it is desirable so to arrange the device that the shutter will be held in the 75

- closed position during shipment, but may be thereafter readily opened without inconvenience to the purchaser. To achieve this result the head is arranged to be releasably held in the closed position. As illustrated in Figures 2 and 4, an indentation may be made in the base member, as for example a notch 46, in such a manner that as the cap is spun into place, the material of the cap, as shown at 47, tends to enter the notch to hold the cap from twisting during shipment, but the initial twist with the fingers will readily bend the projection back into the normal plane and thereafter the cap may be readily opened and closed. If desired, this projection can be again bent into the notch if the tube is to be carried as in a suit case.

- From the foregoing construction it will be clear that a container is provided which is simple and durable both in construction and in operation. It has no exposed operating parts and hence may be kept thoroughly cleaned inside and out. It is adapted for use with containers of varying sorts and in each instance may be caused to make a closure of any degree of tightness desired and by reason of the fact that the openings are in direct alinement with the center of the tube, it may be used in the extrusion of grease and ointments even of a very viscous character and yet may be readily closed when desired.
- Moreover, the shutter element, particularly with a plastic or viscous substance, tends to cut off the extruded material without the necessity of making contact between an instrument such as a tooth brush or the fingers and either the mouth of the container or the material within the container.

It will be obvious that the pin and slot connection may be placed on either end of the shutter when desired, and if desired, the pins may be upon the supporting members, and openings left in the shutter to receive them.

I prefer ordinarily, however, to place the pins in the shutter member as it provides a more suitable structure.

In the form of the invention illustrated in Figure 9, the device is adapted for application to an ordinary bottle in that the neck 11 is attached to a cap 50 having some suitable fastening means for direct attachment to the bottle, as for example, it may be provided with a depending fluted skirt 51 which may be attached to the bottle by crimping around the bead 52 of the bottle neck in the usual manner, there being provided a cork washer 53 between the top of the bottle 54 and the neck 11. The closure itself may be of any of the types heretofore discussed.

In the form of the invention illustrated in Figure 10, there is provided another structure which also may be attached direct to the bottle in which the bottle neck 55 having the usual bead 56, has drilled in its upper surface an opening 57 to receive the pin 58 of the shutter 59, this shutter having its other pin 60 fitted within a slot 61 within the cap. The cap itself is provided with a shoulder 62 adapted to bear upon the top of the bottle neck 55 and lying within the cap is a metallic member 63 having a central opening 64, to receive a resilient washer 65. In this form of the invention the pin 57 extends through a hole in the washer 63 into the recess 58.

In this form of the invention it is preferable to make a pin and slot connection between the cap and shutter rather than between the shutter and the base.

The form of the invention illustrated in Figures 11 and 12 is intended particularly to facili-

tate the pouring of liquids from the container and to this end the structure is provided with two openings. The opening 70, designed for the removal of the liquid, is provided with a spout 71 formed integral with the cap 72, while a small opening 73 is arranged to permit the entrance of air. Each of the openings 70 and 73 passes completely and directly through the cap, shutter and base in the open position, but both are closed by the same movement of the shutter by twisting the cap.

It is preferable to make the smaller opening nearer to the pivot of the shutter to the base, since in this way the larger opening is at the point where the greatest linear movement of the shutter takes place, making it easier to close the wider opening.

In this embodiment it is preferable to provide a shutter seat around each of the openings 70 and 73 so that a liquid tight joint will be provided at both openings.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall between.

Having described my invention, what I claim as new and desire to secure by Letters Patent is:—

1. A closure for a container comprising in combination a base member upon said container having an annular cap-bearing surface facing away from the container, a cap member, said base member and said cap member having each a registering opening concentric with said bearing surface, said cap member having a bearing surface mating with said cap-bearing surface whereby said cap is rotatable on said base member and defines a recess between them, a shutter enclosed within said recess and connected to each of said members, to be movable by the rotation of the cap member to open and close said opening, a shutter-bearing surface surrounding the said opening in said base member and extending upwardly toward the shutter above the level of the recess and means upon the cap member to urge said shutter into contact with said shutter-bearing surface.

2. A closure of the character described for use on a container comprising in combination a base member having a centrally disposed opening therethrough, a cup-shaped cap fitting over said base member and rotatable thereon about the axis of the opening and defining a recess between them, said cap having an opening in registry with the opening in said base and tapering to a thin edge from the periphery toward said opening and presenting a concave upper surface, a shutter within said recess between said cap and said base member operatively connected to both whereby a rotary motion of said cap will move said base member to open or close said opening and there being a rim surrounding the central opening of said base member extending above the level of said recess and the thin edge of said cap being adapted to press the shutter into contact with the rim.

3. A closure of the character described for use on a container comprising in combination a base

member upon the container having a centrally disposed opening therethrough and a raised shutter-bearing surface immediately surrounding said opening, a cup-shaped cap fitting over said base member and having an opening in substantial registry with the opening in said base member, a shutter disposed between said cap and said base member bearing upon said shutter-bearing surface and operatively connected to said cap and base member whereby a partial rotary motion of said cap will move said shutter over said shutter-bearing surface to close the opening and means upon said cap for maintaining said shutter in intimate contact with said shutter-bearing surface throughout the periphery of the latter when said shutter is closed.

4. A closure of the character described for use on a container comprising a base member having a central opening therethrough, a recess in said base member immediately surrounding said opening, a resilient washer carried in said recess and extending slightly above the surrounding surface of the base member to form a shutter-bearing surface, a cup-shaped cap fitting over said base member and having a centrally disposed opening in substantial registry with the opening in said base member, a shutter mounted between said base member and said cap in contact with said shutter-bearing surface and operatively connected both to said base member and to said cap, whereby a slight rotary movement of said cap will move said shutter to open and close said opening, and means upon said cap for maintaining contact between said shutter and said shutter-bearing surface.

5. A closure of the character described for use on a container, comprising in combination a base member having a central opening therethrough, a raised resilient washer carried in a recess in said base to form a shutter-bearing surface immediately surrounding said opening, a cap-bearing surface substantially at the periphery of said base member, both of said surfaces being concentric with said opening, a cup shaped cap embracing said base member, rotatable upon said washer and having an opening in registry with the opening in said base member, a shutter enclosed between said base member and said cap operatively connected to both whereby a rotation of said cap will move said shutter over said shutter-bearing surface to open and close said opening, means for retaining said cap in place for rotation upon said peripheral cap-bearing surface and means upon said cap for maintaining said shutter in close contact with said shutter-bearing surface when in the closed position.

6. A closure of the character described for use on a container comprising in combination a base member comprising a top portion of the neck of the container having a central opening and an annular recess around its outer edge, a cup-shaped cap embracing the end of said neck and having an annular bearing surface in engagement therewith to resist movement along the axis of the opening, a shutter operatively connected to said neck and to said cap whereby a rotary movement of the cap will move the shutter into and out of registry with said opening and a resilient annular washer for exerting pressure between the neck of said container around the periphery of said opening and said shutter when the latter is in registry with said opening.

7. A closure of the character described for use on a container comprising in combination a base member adapted to be applied to the neck of said

container, said base member having an opening in registry with and provided at its upper side with a recess substantially larger than the opening in the neck of said container, a cup-shaped cap embracing said base member and having an opening in registry with and smaller in diameter than the diameter of said recess, an annular resilient washer having its internal diameter substantially equal to the diameter of the recess, fitting within the opening in the base member and a shutter mounted between said washer and said cap and operatively connected to said cap and to said base member whereby a partial rotation of said cap will move said shutter between open and closed positions.

8. A closure for containers comprising in combination a base member, a cap member rotatable on said base member and defining a recess between them, there being registering openings in said base and said cap member, a shutter movable within said recess to open and close said openings and said base member having a rim raised above the level of said recess immediately surrounding the opening therein and having a substantially flat surface to engage said shutter.

9. A closure for containers comprising in combination a base member, a cap member rotatable on said base member and defining a recess between them, there being registering openings in said base and said cap member, a shutter movable within said recess to open and close said openings and said base member having a rim raised above the level of said recess immediately surrounding the opening therein and having a substantially flat surface to engage said shutter, and means upon said cap immediately above said rim for pressing said shutter directly against said rim.

10. A closure for containers comprising in combination a base member upon said container, a cap member upon said base member, one of said members having an annular rim extending above its surface projecting toward the other member to form a narrow concentric bearing surface transverse to the axis of the closure, the area of said bearing surface being materially less than the area of the member inside of said surface, and the other of said members having a bearing surface mating with said first mentioned surface whereby there is formed between said members a recess having a substantially circular peripheral wall, a shutter having one of its ends pivotally fixed to one of said members and the other end pivoted to the other of said members, both of said pivots being enclosed within said cap, said shutter being substantially the thickness of the depth of the recess in the immediate vicinity of the opening, and means to hold said members with said bearing surfaces in contact, whereby the position of said cap member is maintained against tilting by the engagement of said bearing surfaces and a predetermined and relatively fixed pressure may be maintained between the shutter and the base member adjacent to the opening.

11. A closure of the character described for use on a container comprising in combination a base member having a central opening therein, a peripheral annular cap bearing surface transverse to the axis, of materially less area than the remainder of the base member, said base member being also provided with an external groove, and having a shutter bearing surface of materially less area than the area of said base member within said cap bearing surface, a cap

embracing the end of the base member bearing against said cap bearing surface, said cap member having lateral walls bent over into said groove to retain said cap member in place for rotary motion without axial lost motion, a shutter carried between said cap and said base member of larger area than said shutter bearing surface, operatively connected to said cap, and movable to open or closed position, and means upon said cap to keep said shutter in firm contact with said shutter bearing surface when in closed position.

12. A closure for containers comprising in combination a base member, and a cap member mounted on said base member and defining a recess between them; there being registered openings in said base member and cap member, a shutter movable within said recess to open and close said openings, means for moving said shutter, said base member having a rim raised above the level of the recess, immediately surrounding the opening therein and having a substantially flat surface to engage said shutter and means upon said cap immediately above said rim for pressing said shutter against said rim.

13. A closure for a container comprising in combination a base member, a cap member upon the base member, said members having two sets

of bearing surfaces, cooperating to retain said cap member upon the base member and to prevent tilting of the cap member, said base member and said cap member having substantially parallel and flat spaced surfaces, a shutter of substantially uniform thickness between said flat surfaces, and said flat surfaces having registering openings in position to register with a corresponding opening in the shutter in one position of the latter and said flat surfaces being of such contour as to exert greater pressure upon the shutter at the edges of the opening and means for moving said shutter.

14. A closure for containers comprising in combination a base member, and a cap member mounted on said base member and defining a recess between them; there being registered openings in said base member and cap member, a shutter movable within said recess to open and close said openings, means upon rotation of said cap member for moving said shutter, said base member having a rim raised above the level of the recess, immediately surrounding the opening therein and having a substantially flat surface to engage said shutter and means upon said cap immediately above said rim for pressing said shutter against said rim.

PERCY M. THORN.
